REFUSE INCINERATOR

John W. Hebert, Bay City, Mich., assignor to
Valley Welding & Boiler Co., Bay City, Mich.

Application September 20, 1947, Serial No. 775,261

2 Claims. (Cl. 219—19)

1

This invention relates to incinerators, and more particularly to an incinerator provided with an electric heating element or unit for assisting in drying the refuse preparatory to combustion.

One of the prime objects of the invention is to design a disposal unit in which air inlet openings are provided in the combustion chamber directly adjacent the heating element so that incoming air current flow over and around the heating element, and direct flame and heat away from the unit proper, said air currents further drying the refuse immediately around the element to the end that it will burn prior to the burning of the main mass or body and maintain the heating element at a somewhat lower temperature than would otherwise be possible if no air flow were provided at this point.

Another object is to provide air inlet openings in the combustion chamber side wall directly adjacent the heating element to enable combustible material present in the incinerator to have a reasonable low temperature ignition point, thus necessitating only low initial heating element temperature.

A further object is to provide air passages or openings in the side wall of the combustion chamber directly adjacent the heating element and in substantially horizontal alignment with the openings in the smoke passage, so that the incoming air stream or streams carry the heat away from the heating element by conduction, thus preventing over-heating of the heating element, and simultaneously aiding in the dehydrating process necessary with wet, soggy refuse.

To the accomplishment of the foregoing and related ends, said invention then consists in the means hereinafter described, and particularly pointed out in the claims, the annexed drawing and following description setting forth, in detail, certain means and one mode of carrying out the invention, such disclosed means and mode illustrating, however, but one of various ways in which the principle of the invention may be used.

In the drawing:

Fig. 1 is a sectional, side-elevational view of my incinerator showing the heating element in place, the arrows indicating the direction of flow of incoming air currents.

Fig. 2 is a transverse, sectional view taken on the line 2—2 of Fig. 1 and looking toward the front of the incinerator.

Fig. 3 is a top plan view.

In incinerators of the character described, the heating unit is utilized to produce drying temperature so that the refuse will be considerably

2

dried before final ignition takes place; thus obnoxious odors and smoke are eliminated and deleterious effects are reduced.

In practice, I find that where the heating unit is covered with soggy refuse, the heat generated by the heating element dries the refuse directly in contact with said element and upon ignition further heats the heating unit to the extent that the heating element is unreasonably short-lived, even though the automatic control of the unit operates to cut off the electric current when the temperature reaches a predetermined point, and this is primarily due to the fact that the heating unit is covered with refuse; the heat generated by the element is retained therein, and the temperature of the heating element is further raised by the burning of the surrounding refuse, and these disadvantages I have cured in the instant invention in which the incoming air currents serve to dry the refuse immediately surrounding the unit, so that it burns prior to the main mass or body, these same air currents tending to cool the heating unit and conduct the heat away from the unit during the burning process.

Referring now to the drawing in which is shown the preferred embodiment of my invention. The incinerator comprises an insulated casing 5 provided with a receiving or combustion chamber 6 therein, this chamber being disposed above an ash drawer 7 which is operable to admit air in a manner to be presently described.

Grate supports 8 are disposed between the chamber 6 and the removable ash drawer 7, and a movable grate 9 is disposed above the grate supports and is operable by a shaker bar 10 so that to-and-fro movement can be imparted thereto.

The instant incinerator is of downdraft design, and a flue pipe 11 is provided in the rear of the combustion chamber for conducting the products of combustion up the flue 11 and through pipe 12 to the atmosphere, and a hinged cover 13 is secured to the open top of the casing to permit dumping of refuse etc. into the receiving chamber.

The electric heating unit is generally designated at 14; it is mounted on the front wall of the receiving chamber 6 by means of a strap or bracket 15, and is supported above the grate 9 so as to project upwardly into the receiving chamber.

As shown in Fig. 1, the electric heating unit 14 is supported on the front wall 16 of the combustion chamber and is connected to the inner end of a tubular member 17, the outer end of which

What I claim is:

1. A downdraft refuse incinerator comprising an outer casing, a combustion chamber therein and spaced from the outer casing to provide air passages therebetween, a smoke flue communicating with said chamber, openings in the bottom of the incinerator casing and upper end of the chamber respectively, providing continuous air passages from the bottom of the incinerator to said flue, an electric heating unit mounted in the combustion chamber adjacent the front wall thereof, and a plurality of openings in said front wall directly adjacent to the heating unit for admitting air from said passages at a point below the lower end of the smoke flue.
2. A downdraft incinerator of the class described comprising an insulated outer casing, a combustion chamber therein and spaced from the outer casing to provide air passages therebetween, a smoke flue in the rear of the combustion chamber, air inlet openings in the lower end of the outer casing and in the upper end of the combustion chamber respectively, an electric heating unit including an annulus substantially round in cross section mounted in the chamber directly adjacent one wall thereof, and a plurality of air inlet openings in one wall of the combustion chamber directly adjacent to the annulus of the heating unit and in substantial horizontal alignment therewith.

projects through a sleeve 18 in the rear wall of the incinerating unit, and is rigidly connected thereto by means of retaining units (not shown).

The heating element is preferably, but not necessarily, circular in shape to provide an annulus 19 of round cross section, and suitable wires 20 lead around the annulus, as shown and described in application for patent by Charles B. Curtiss, filed April 17, 1947, Serial No. 742,133, issued May 10, 1949, as Patent No. 2,469,534.

An outlet box 21 is affixed to the free end of the tubular support 17 for accommodating cable connections (not shown) with a suitable source of electrical energy, and while in the present instance the electric heating unit is shown as circular in shape, it will be readily understood that it can be of any desired shape or design.

A plurality of air inlet openings 22 are provided in the front wall 16 of the combustion chamber as shown, these openings being directly adjacent to and in horizontal alignment with the heating unit 14, so that air flows from the space 23 between the outer shell and the combustion chamber and over and around the unit 14.

Openings 24 are also provided directly adjacent to the upper end of the combustion chamber, and similar openings 25 are provided in the base and bottom wall 26, so that incoming air flows upwardly in the space 23, thence through the openings 24, thence downwardly through the refuse, and thence up through the smoke flue and pipes 11 and 12 respectively, a portion of the air entering through the openings 22, flowing over and around the heating unit, and thence directly across the smoke flue 11.

From the foregoing description, it will be obvious that I have designed a very simple, practical, and effective drying and heat dissipating arrangement and construction for the heating units of incinerators and the like.
